UNITED STATES PATENT OFFICE.

SAMUEL GREENBERG, OF NEW YORK, N. Y.

CHILD'S OVERCOAT.

Application filed February 5, 1927. Serial No. 166,184.

The present invention is concerned with improvements in children's overcoats, particularly with the provision of a coat which may be conveniently lengthened without any need for sewing, and by the simple expedients of ripping out a few tacks, unfolding the hem and pressing the coat.

A circumstance which is a material factor in the manufacture and sale of children's overcoats, is the fact that growing children soon outgrow the coat, and the coat must either be lengthened or discarded, in consequence, most purchasers hesitate to invest in an expensive overcoat for a child due to the comparatively short life of the coat.

The present invention overcomes this difficulty by the provision of a coat which may be readily lengthened without any trouble and without the need for sewing.

Further objects of the invention are to provide a coat which will be of neat and attractive appearance, both before and after the lengthening operation.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a fragmentary view showing the inside of a child's overcoat and with parts broken away and in section for the sake of clearness.

Fig. 2 is an enlarged longitudinal sectional view on the line 2—2 of Fig. 1.

Fig. 3 is a view similar to Fig. 2, but showing the tacks removed and the hem let down.

Fig. 4 is a fragmentary view of the inside of the coat showing the position of the parts during the lengthening of the coat.

Fig. 5 is a transverse sectional view on the line 5—5 of Fig. 1.

In the drawings I have used the reference numeral 10 to designate the body portion of a coat, the lower edge of which is turned upwardly and inwardly to define a hem portion 11, and the side edges of which are turned inwardly to define flaps 12 lending a finishing appearance to the edge of the coat where the buttons and buttonholes are

to be applied. The flap portion 12 is also provided with an upwardly and inwardly turned hem 13 overlying the adjacent hem 11.

The lining of the coat designated at 14 is connected at one edge to the inwardly turned flap as by a line of stitching 15. This line terminates just short of the lower edge of the body 10 and is turned upwardly and inwardly to define a hem 16, the edge of which is secured to the edge of the hem 11 by a line of stitching 17.

The upwardly turned and connected body hem 11 and lining hem 16 are prevented from dropping gravitationally downwardly by a few tacks 18 connecting the lining, body, and upper connected edges of the two hems. The lower edge 19 of the folded lining and the lower edge 20 of the folded flap 12 may also be conveniently retained against movement away from the body of the coat by the use of a tack or two, such as the tacks 21.

In view of the fact that the hem 16 is slightly shorter than the hem 11, it will be evident that when the coat is lengthened, there will still be an edge of the body projecting below an edge of the lining. Lengthening is accomplished merely by manually ripping out the tacks 18 and 21, folding the connected hems 16 and 17 downwardly from the position of Fig. 2 to the position of Fig. 3 and pressing the coat; it being altogether unnecessary that any sewing be done to accomplish the alteration. The hem 13 of the flap 12 will also fold outwardly, producing a finished corner at the lower end of the flap. The coat presents a neat and attractive appearance both prior to and subsequent to the lengthening operation, since at all times the seams connecting the coat and lining are concealed.

Obviously a similar arrangement might be used in connection with the sleeve of the coat if desired, and various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claim.

I claim:

A child's overcoat including a body and a lining, each formed with inwardly and upwardly turned concealed hems arranged in the space between the body and lining having their upper edges secured together, said hems being unconnected to the body or lining save through readily manually removable tacks passed through the connected up-

per edges of the hems and through the lining and body, the side edge of the body including an inwardly turned flap connected to the edge of the lining and at its lower edge being turned upwardly and inwardly with the lining and tacked. 10

SAMUEL GREENBERG.
